UNITED STATES PATENT OFFICE

MILLARD BOWEN LUCKER, OF BENTON HARBOR, MICHIGAN, ASSIGNOR TO AUTO SPECIALTIES MANUFACTURING COMPANY, A CORPORATION OF CALIFORNIA

RECOIL CHECK

Application filed July 2, 1928, Serial No. 290,020.

The present invention relates to devices for absorbing and checking the recoil of vehicle springs and the like and has for its object to produce a device of this kind that shall be simple and rugged in construction, efficient in operation and capable of being quickly and easily adjusted to secure the desired amount of resistance, both initially and to take up wear.

10 In carrying out my invention, I make use of a rotatable drum connected in any usual and suitable manner so that it turns in one direction when the spring with which it is associated is compressed and in the opposite direction when the spring expands. Co-operating with the drum is a brake band controlled in a simple and novel manner so as to operate most efficiently. The ends of the band are connected to a swinging anchor 15 which, when it moves in one direction tightens the band whereas, when it swings in the opposite direction, the band is loosened. A spring acts on the anchoring member so as to tend constantly to swing it in a direction 20 to tighten the band. This movement of the anchoring member is limited by an adjustable stop which determines the degree to which the band might be tightened. The braking action does not depend upon the spring, however, because its function is to hold the band 25 against the drum with a sufficient degree of pressure that the band will grip the drum and cause the drum positively to swing the anchoring member and bring about the desired braking pressure by causing the band 30 to pull the anchoring member in the proper direction.

The various features of novelty whereby my invention is characterized will herein 35 after be pointed out with particularity in the claims; but, for a full understanding of my invention and of its objects and advantages, reference may be had to the following detailed description taken in connection with 40 the accompanying drawings, wherein:

Figure 1 is a side elevation of a device arranged in accordance with my invention, mounted on the frame of an automobile; Fig. 2 is a section on line 2—2 of Fig. 1, on an enlarged scale; Fig. 3 is a side view of the

device, on the same scale as Fig. 2, the cover being removed and fragments of the eyes connecting the band to the anchor being broken away; Fig. 4 is a section taken approximately on line 4—4 of Fig. 1; and Fig. 5 is a top plan view of the device with the cover or casing shown in section.

Referring to the drawings, 1 represents a base that may be in the form of a comparatively flat plate. Projecting from one side of the base is a post 2. A brake drum 3 is rotatably supported on the post. In the arrangement shown, the inner end or side of the hub 4 of the brake drum bears against a flat face 5 on the base at the inner end of the post. The bearing opening in the drum does not extend entirely through the hub of the drum, but it is in the form of a socket 6 whose depth is slightly greater than the length of the post, so that the free end of the latter will not bottom in the socket. The hub on the drum is continued in the outward direction in the form of a heavy boss 7. A heavy screw 8, having on the outer end a head 9, extends through the boss 7 and into the post. In order to lock the screw against accidental turning when the device is in use, I insert through the rear side of the base a screw 10 that abuts against the end of the screw 8.

Partially surrounding the drum is a brake band consisting preferably of a flexible steel strap 12 lined with a thick layer 13 of leather or other material suitable for brake linings. Connected to the ends of the straps are terminal members 14 and 15 in the form of shackles. The straps are preferably secured to the terminal members by passing the ends through suitable openings 16 in the shanks or stems of said members, and then folding the ends back so that they overlie sections of the strap inwardly from the terminal members, as indicated at 17 and 18. The sections 17 and 18 are then welded to the underlying main portions of the strap.

The shackles are pivotally connected to a swinging anchor 20. This anchor is in the form of a short heavy bar lying beyond the periphery of the drum and more or less radial to the drum. It is pivotally supported by a

pin 21 passing through the same and into the base at the end farthest removed from the drum. As a matter of fact, the pin 21 may be a cylindrical lug or trunnion integral with and projecting from the base. The body portion of the anchor fits into the two terminal members or shackles and is pivotally connected to the same by means of pins 22 and 23. The pin 22 passes through the anchor in the vicinity of its free end, while the pin 23 is located between the pins 21 and 22. In other words, the radius from the pivotal axis of the anchor to the pin 22 is greater than the corresponding radius to the pin 23.

The result of this structure is that if the anchor is swung in either direction, the pin 22, and therefore one end of the brake band, travels faster and farther than does the pin 23 and the other end of the brake band. When the anchor swings in the clockwise direction, as viewed in Fig. 3, the result is to loosen the band on the drum, because the upper end moves upwardly faster than does the lower end. If the anchor is swung in the counterclockwise direction, the upper part of the band is pulled down faster than the lower portion drops, therefore the band will tighten on the drum. It will thus be seen that if the band be held against the drum with some initial pressure so as to produce more or less frictional resistance to rotation of the drum, a rotation of the drum in either direction will cause the anchor to swing or tend to swing through the agency of the brake band itself. In other words, if the drum is rotated in the clockwise direction as viewed in Fig. 3, it will cause the under portion of the band to pull on the pin 23 so as to swing the anchor downward. Consequently there will be a closing action of the band upon the drum. When the drum is turned in the counterclockwise direction, as viewed in Fig. 3, the upper part of the band comes into play to pull the anchor up, thus loosening the band.

If now the base member be fastened to the frame of an automobile, as indicated at A in Fig. 1, and there is attached to the boss 7 an operating lever 25, and the free end of the operating lever is connected by a suitable rod 26 to an underlying automobile axle (not shown): it will be seen that the characteristics of the braking device may be utilized to permit the corresponding automobile spring to close without meeting any considerable resistance from the recoil check because the drum will be turning in the counterclockwise direction as viewed in Fig. 3. However, when the spring starts to expand or rebound, such movement will result in a turning of the brake drum in the clockwise direction, causing the brake band to be tightened upon the drum and retarding its rotation and consequently retarding and checking the rebound movement of the spring.

Unless some controlling means are pro-

vided, the brake band can be drawn so tightly against the drum as to lock it instead of simply retarding its turning movement. I have therefore provided a stop to limit the swinging movement of the anchor in a direction to bring about a braking action. In the arrangement shown, the base is provided with a lug 27 at the side of and at some distance from the anchor. A screw 28 extends through this lug in the path of the anchor when the latter swings. The screw is so adjusted that the anchor will strike the end thereof when moving in the direction to tighten the band, before the band grips the drum with sufficient force to lock it against rotation. It will be seen that by adjusting the screw the ultimate braking action may be varied within comparatively wide limits, thus permitting the device to be properly adjusted for vehicles of various weights and springs of various kinds. Furthermore, when wear takes place in the band, so that the braking action diminishes, the stop may be adjusted so as to increase the braking action again to the point at which it originally stood.

The braking action results through the driving of the swinging anchor by means of the brake band itself and does not depend upon spring means or the like. However, it is necessary that there be initially sufficient friction between the band and the drum to cause the band to be gripped and start the anchor in a direction to tighten the band, whenever a braking action is required. If there were initially sufficient traction between the drum and the brake band, wear in the band, and other causes, might result in a sufficient looseness of the band to prevent the device from functioning properly as a brake. I have therefore provided a small spring whose purpose is at all times to keep the brake band under a small tension. In the arrangement shown, I have provided the base of the device with a lug 29 arranged on the opposite side of the anchor from that on which the lug 27 is located. Between the lug 29 and the side of the anchor, near the free end of the latter, is a coil spring 30 under initial compression. This spring tends constantly to force the anchor down against the stop, thus insuring that the band will be held taut. To provide for adjusting the compression of the spring, one end of the spring may rest against the inner end of a screw 31 screwed into the lug 29 and provided with a guide finger 32 extending inwardly into the spring.

The mechanism just described may be enclosed in any suitable way. In the arrangement shown, there is a pan-shaped sheet metal casing 35 fitting over the main portion of the base and over the top and bottom edges. The base itself has at the ends ear-like extensions, and the casing is provided

with projections or ears 36 overlying these end portions of the base. The device may be secured to the frame of a vehicle by means of suitable bolts such as indicated at 37 in Figs. 1 and 2. These bolts may pass through registering openings 38 in the elements 36 and the underlying portions of the base. Therefore the same bolts serve to secure the casing in place and to fasten the device as a whole to the supporting structure.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In a device of the character described, a rotatable drum, a stationary pivot, a rigid swinging anchor mounted at one end on said pivot and having its free end extending toward the drum, a brake band on the drum, and a connection between each end of the band and the anchor at a point between the pivotal axis of the anchor and the drum, the connection between one end of the band and the anchor being nearer the drum than the connection between the other end of the band and the anchor.

2. In a device of the character described, a rotatable drum, a stationary pivot, a rigid swinging anchor mounted at one end on said pivot and having its free end extending toward the drum, a brake band on the drum, a connection between each end of the band and the anchor at a point between the pivotal axis of the anchor and the drum, the connection between one end of the band and the anchor being nearer the drum than the connection between the other end of the band and the anchor, and a spring tending to hold the anchor in the position in which the band is drawn most tightly.

3. In a device of the character described, a rotatable drum, a stationary pivot, a rigid swinging anchor mounted at one end on said pivot and having its free end extending toward the drum, a brake band on the drum, a connection between each end of the band and the anchor at a point between the pivotal axis of the anchor and the drum, the connection between one end of the band and the anchor being nearer the drum than the connection between the other end of the band and the anchor, a spring tending to hold the anchor in the position in which the band is drawn most tightly against the drum, and an adjustable stop to limit the movement of the anchor in the direction in which the spring tends to swing it.

4. In a device of the character described, a base, a drum rotatably mounted on the base, an anchor member lying outwardly from the

drum and approximately radial thereto, a pivotal connection between the outer end of said member and the base to permit said member to swing about an axis parallel with the axis of rotation of the drum, a brake band extending over the drum, a connection between one end of the band and the inner end of said member, means connecting the other end of the band to said member at a point between its pivotal axis and point of connection of the opposite end of the band, an adjustable stop to limit the swinging movement of the anchor member in one direction, and a spring tending constantly to hold said member against the stop.

5. In a device of the character described, a rotatable drum, a brake band extending over the drum, a pivotally-supported anchoring means connected to the ends of said band in such a manner that upon a rotation of the drum in one direction one end of the band exerts a pull on the anchoring means to draw the other end of the band against the drum, while upon rotation of the drum in the opposite direction the latter end of the band exerts a pull on the anchoring means in a direction to loosen the band on the drum, an adjustable stop to limit the swinging movement of the anchoring means in a direction to tighten the band, and a spring tending constantly to hold the anchoring means against said stop.

6. In a device of the character described, a flexible steel brake band, terminal members each having an opening therethrough near one end, the end portions of the band being passed through said openings and folded back upon the band inwardly from the terminal members, and the overlying portions of the band in contact with each other being welded together.

7. In a device of the character described, a base, braking mechanism mounted on the base inwardly from both ends of the latter, a casing extending over said mechanism and resting against the base, said casing having at the ends ears lying against the base, and the base and the ears having registering openings therethrough to receive elements to secure the casing to the base and simultaneously to secure the base to a support.

In testimony whereof, I sign this specification.

MILLARD B. LUCKER.
